EARTH ANCHOR

Roy O. Mead, Gilroy, and Charles Grunsky,
San Francisco, Calif.

Application September 22, 1951, Serial No. 247,778

13 Claims. (Cl. 189—92)

1

This invention relates to an improvement in earth anchors, and more particularly to the type anchor adapted to be inserted in a prepared hole in the ground and then extended to serve as a brace for use in connection with a guy wire for staying telegraph, telephone, and electric trolley poles, stacks, derricks, and the like.

The devices of the prior art are unduly complicated in that numerous parts are required, and in some cases machined components, such as, helical screws, cams, spring arrangements, rack and pinion and other types of gears or any combination thereof also add to the expense of manufacture of these devices. The purpose of such components is ordinarily to project the flukes of the anchor into a holding position, to withdraw the flukes or to lock them in position. Quite frequently such arrangements require that complicated tools be used for forcing the flukes to their holding positions. Other prior art devices are required to be set (or expanded) by manual labor, such as pounding the flukes into position, and in most cases such expansion of the flukes disturbs the earth surrounding the prepared hole with attendant loss in holding power of the completed installation.

Accordingly, an important purpose of the present invention is the provision of an earth anchor which is sufficiently non-complex as to admit of economy in the manufacture thereof, yet is rugged enough to serve as a suitable fastening. Preferably, the structure of the present invention comprises a plurality of stacked blades or disks which may be longitudinally aligned preparatory to insertion into the previously bored ground hole. Some or all of the blades may then be extended transversely into the surrounding ground to occupy adjacent holding positions. In order that these blades may present a large anchoring area, the axis of extension is taken at a point near the blade peripheries. Thus a guide pin is inserted through all of the blades at this point to serve as the pivot for the blades when they are extended. A shoulder or flange is eccentrically secured to this pin and serves in one purpose to prevent longitudinal movement of the blades. A stub is positioned on the upper surface of the top blade to serve as a blade driving means. The shoulder is also adapted to receive an anchor driving tool which has an arm extended to project along the upper surface of the top blade, thus forming an abutting engagement with the blade driving means. With this arrangement rotation of the anchor driving tool serves to expand the blades to their holding position.

2

The present invention may be modified to the extent that a tubular sleeve eccentrically flared at one end suffices to replace the guide pin and shoulder. The flared end of this sleeve serves as the attachment for the anchor driving tool and in so doing permits slight tow-in beneath the flare and hence provides a desirable gripping surface for the driving tool. Such a component is less expensive to manufacture than the guide pin and eccentrically positioned shoulder combination and hence is desirable, as well, from the economical standpoint.

The anchor driving tool may comprise a sleeve which is adapted to fit over the auger which originally drilled the hole, and hence may afford an extremely powerful driving mechanism. Rotation of the auger and the sleeve attachment serves to move the upper blade to its extended position which thus places the stub at a position radially opposite from the point of greatest shoulder eccentricity. Hence the arm of the anchor driving means falls short of engagement with the stub and further rotation of the top blade is prevented.

25 This feature of the invention is very desirable as it permits the employment of a powerful blade extending means which otherwise would not be possible because the angle or revolution of the driving means would necessarily be confined to less than 360°. Power driving means are ordinarily designed for continuous rotation and hence structural changes would otherwise necessarily be demanded.

In order that successively lower positioned 35 blades of the stack may be moved to their extended positions, depending lugs are provided along the periphery of the upper blades. The purpose of these lugs is to engage the next successive lower blade and permit rotation of it to its extended position in accordance with movement of the blade adjacently positioned above. In the alternative and also to simplify the manufacture of the blades, they may be dented near the peripheries thereof to provide downwardly 40 extending projections which suffice to replace the lugs. The blades may be further modified to include strength adding corrugations providing such corrugations lie along areas centered at the axis of extension.

An anchor bolt may serve as the vertical extension from the anchor to which the guy lines may be attached. This bolt may be secured to the guide pin by means of welding, bolting or otherwise as desired. Preferably, however, the anchor bolt extends through the guide pin and is secured

against withdrawal therefrom by means of a nut attachment on the lower end of the bolt. Further, it is usually desirable to provide a keel to secure the lower blade against rotation.

Thus the instant invention provides a relatively simple yet rugged structure which is readily extended into operating position by the accessible auger drilling tool.

Accordingly, among the objects of this invention is: the provision of an anchoring device capable of quick instalment; the provision of an anchor device which is extremely rugged in character; the provision of a device which when extended presents a large holding area; the provision of a device which is capable of being expanded into the surrounding earth with minimum disturbance to the earth; the provision of a device which may be readily extended by a powerful driving means; the provision of a device which is cooperatively expanded from a main driving means; and the provision of a device which is relatively free from machined parts and hence economical in manufacture.

Other and further objects of the present invention will be apparent from a reading of the following detailed description thereof when taken in conjunction with the accompanying drawings wherein:

Fig. 1 is a plan view showing typical structure embodied in an anchor device of the present invention;

Fig. 2 is a plan view of the device of Fig. 1 as shown in its extended position;

Fig. 3 is a cross-sectional view of the structure of Fig. 1 taken along the plane 3-3 and looking in the direction of the arrows;

Fig. 3a is a detailed view in perspective of the guide pin, eccentrically positioned shoulder and the anchor bolt in position;

Fig. 3b is a view in perspective showing a modified form of an anchor blade positioned for revolution about an eccentrically flared tube; and,

Fig. 4 is a view in side elevation of the structure of Fig. 2 as viewed along the plane 4-4 and looking in the direction of the arrows.

Referring now to the drawings, and first particularly to Figs. 1 and 2, a set of disks or blades numbered 1, 3, and 5, respectively, are adapted to serve as the ground securing means for the anchor of the present invention. For purposes of illustration, three such blades are shown, but obviously two or more than three could be suitably employed. An axis of extension is provided for the blades by a guide pin 7 which is best shown in Fig. 3a. As may be seen in Fig. 1, the guide pin 7 is positioned near the periphery of the blades so that the blades in their expanded position (as shown in Fig. 2) may present a very large holding area. The guide pin 7 is provided with an eccentrically positioned flange or shoulder 9, which shoulder serves in one purpose to prevent longitudinal movement of the blades (Fig. 3).

A vertical anchor bolt 11 is extended from the anchor to serve as the attachment for the guy wires at or above the ground surface. This bolt is secured to the anchor at the guide pin 7 by means of the nut 13 which is adapted to bear against the lower end of the guide pin. A washer or collar 15 may be provided between the guide pin 7 and the nut 13 if desired. Obviously the anchor bolt could be secured to the guide pin by means of threaded engagement or welding or other means of attachment. The lower blade 5 is preferably secured to the guide pin 7 by means

of the annular weld 16. Thus a rigid attachment is completed from the anchor rod to the blades. Also, welded or bolted to the under side of blade 5 is a keel 5' which is adapted to extend into the earth and thus prevent movement of the lower blade.

As was earlier mentioned, it is highly desirable that a very powerful driving means may be employed to extend the blades into the surrounding earth. However, the expanded position of the blades, as is shown in Fig. 2, makes it apparent that the top blade 1 is only extended through an angle of 240° (in the case of the three-blade anchor illustrated) from the bottom blade 5, and the middle blade 3 is moved 120° from its original position. The angle of revolution of each blade may be determined from the expression

$$N\left(\frac{360^\circ}{n}\right)$$

where n is the total number of blades and N is the blade number in the stack with the lowermost blade being number 0. Unless a means of disengaging the driving device at the proper instant is provided, the blades would necessarily dig up the surrounding earth due to extensive revolutions, and hence loss in holding power of the anchor would result. The present invention, accordingly, provides a method of disengaging the blades from the driving means when they have reached their desired holding positions. The driving means may comprise the auger (not shown) which was originally employed to drill the anchor hole. This auger may be fitted with a sleeve extension 17 (Figs. 3 and 4) which is adapted to slidably fit over shoulder 9 and to rest on the top surface of the blade 1. The bore 18 of the sleeve need only be large enough to accommodate the anchor bolt, provided the sleeve is sufficiently flanged and recessed to enable it to encompass the shoulder 9. This sleeve is further provided with an arm 19 which extends along the upper surface of blade 1. An upriser or stub 21 is located on the upper surface of blade 1, at a position which is opposite the extremity of the arm 19 when the blades are in their stacked condition, as shown in Fig. 1. An engaging abutment is formed between the arm and stub so that rotation of the auger extends blade 1 into the surrounding earth. This blade is the only one which is moved during the initial 120° rotation of the auger. A depending lug 23 is provided at a point on the periphery of blade 1. The location of this lug is such that after the disk 1 has been revolved through an angle of 120°, the lug 23 engages disk 3, thereby imparting movement to this blade. A depending lug 24 is also provided at a point along the periphery of blade 3 such that it engages the periphery of blade 5 after the blade 3 has been moved through an angle of 120°. Thus such engagement insures against any excessive revolution of blade 3.

As the shoulder 9 is eccentrically positioned on the guide pin 7, the axis of revolution of the sleeve 17 is displaced from the axis of revolution of the blades. This displacement is such that abutting engagement between the arm 19 and stub 21 exists only until the upper blade 1 is moved to its desired position. Due to the eccentricity of the flange or shoulder 9, the sleeve 19 then disengages from the stub 21 and the auger is free to rotate.

In Fig. 3b there is shown a modified blade 27 positioned for rotation about a tube 29 which is eccentrically flared at the end 29' thereof. The

blade 27 may be stamped from a metal blank, in which case a corrugation 31 is provided to strengthen the blade. The blade is dented near its periphery to form a downwardly extending projection 33, the purpose of which is identical to that of the stubs 23 and 24. When a number of such modified blades are employed in an anchor device, the corrugations and indentations must be so located in the respective blades that they nest in the corrugations and indentations of the adjacently lower positioned blades when the blades are arranged in stacked relationship. Obviously the corrugation 31 defines an arc of a circle whose center lies along the axis of extension, i. e., along the axis of tube 29. The tube 29 may be formed, for example, by rolling or off center boring in such manner that the flare 29' is eccentric with respect to the tube axis. Thus sleeve 17 may tend to toe-in against the tube 29 beneath the periphery of the flared end 29', thereby providing desirable engagement between this driving tool sleeve 17 and the flared tube 29 while correcting for any slight misalignment, the upper blade 27 being rotated through engagement of auger arm 19 with a stub 21' in the manner of the showing of Figs. 3 and 4.

It should be re-emphasized that the instant invention is capable of having the blades thereof extended to the desired operating position by the employment of a simple attachment for the drilling tool. Further reiterations should include mention of the fact that the powerful driving means is automatically disengaged from the blades when they have been moved to their operating position. Also, since the blades occupy a rather extensive ground contacting area, and as their expansion is affected with minimum disturbance of surrounding soil, any lateral movement of the complete installation is reduced to a minimum.

What is claimed is:

1. In an earth anchor, a plurality of blades, a guide pin eccentrically positioned relative to each of the blades for securing said blades in stacked relationship and for permitting rotation of the blades about said pin as an axis, a blade motion control means encompassing the end of the guide pin and located so as to be eccentric relative to the pin axis, said eccentric blade motion control means being adapted to receive and locate an anchor driving element and permit of rotation of said element thereabout, and means for rotating the blades in sequence with the angle of rotation of the upper blade being less than 360° and being limited by the eccentricity of the blade motion control means to an angular motion of

$$360^\circ - \frac{360^\circ}{n}$$

where n represents the total number of blades in the stack.

2. An expanding anchor comprising a plurality of blades adapted in a closed state to be stacked one above the other, a guide pin extending through all of the blades in the vicinity of the blade periphery for locating the blades relative to one another, means for fixedly securing the lowermost blade of the stack to the guide pin, a shoulder member located at the opposite end of the guide pin and surrounding the guide pin for longitudinally locating the stack of blades and preventing longitudinal motion of the said blades with respect to each other, said shoulder being of generally circular shape and so surrounding the upper end of the guide pin that

its center is eccentric to the axis of the guide pin, a blade driving means forming a part of the uppermost blade of the stack and located on the upper surface of the said blade, said shoulder member being adapted to receive an anchor driving tool having an outwardly-extending arm adapted to provide abutting contact with the blade driving means in a closed-blade position, so that with rotation of the anchor driving tool arm 10 the said upper blade is correspondingly rotated through an angle measured by the maximum eccentricity of the shoulder member relative to the guide pin, and means for connecting all of the blades above the lowermost of the stack for 15 rotation in sequence in such manner that the uppermost blade of the stack is capable of rotation through the greatest angle and the remaining connected blades of the stack in sequence are adapted to be rotated through angles which are 20 successively less than that of the upper blades. 3. In an earth anchor, a plurality of blades, a guide pin for securing said blades in closely stacked relationship and extending through said blades to permit rotation thereof about an axis 25 eccentric to the center of each blade, a blade driving means connected to the uppermost blade of the stack, means for fixedly locating the lowermost blade of the stack relative to the guide pin, a driving tool connecting means adapted to 30 receive and locate an anchor driving tool and to permit rotation thereof eccentrically about the guide pin so that the anchor driving tool in one position is in abutting contact with the blade driving means and following a rotation of the 35 blade driving means through an angle of

$$360^\circ - \frac{360^\circ}{n}$$

where n equals the number of blades in the stack, 40 is permanently free from abutting engagement with the blade driving means, and means for sequentially connecting the said blades for rotation with each blade of the sequence being connected to rotate following a rotation of the next uppermost located blade through an angle of

$$360^\circ - \frac{360^\circ}{n}$$

4. The anchor claimed in claim 3 comprising, 50 in addition, a keel extending in a plane substantially normal to the plane of the lowermost blade and secured to the lowermost blade.

5. The anchor claimed in claim 4 comprising, 55 in addition, an anchor rod extending through the guide pin.

6. An expanding anchor comprising a plurality of disks adapted in a closed state to be stacked one above the other, a guide pin extending through all of the disks in the vicinity of the disk circumference for locating the disks relative to one another, means for fixedly securing the lowermost disk of the stack to the guide pin, a shoulder member located at the opposite end of the guide pin and surrounding the guide pin for longitudinally locating the stack of disks and preventing longitudinal motion of the said disks with respect to each other, said shoulder being of generally circular shape and located in an eccentric position relative to the axis of the guide pin, means secured to the uppermost disk of the stack to enter into abutting engagement with the driving arm of an anchor driving tool adapted to be located by the said shoulder for rotation so that abutting contact is established with the disks in a closed position and capable of being maintained

during rotation of the anchor driving arm through an angle measured by the maximum eccentricity of the shoulder member relative to the guide pin, and means for connecting all of the disks above the lowermost of the stack for rotation in sequence in such manner that the uppermost disk of the stack is adapted for rotation through the greatest angle and the remaining connected disks of the stack in sequence are adapted to be rotated through angles which are successively less than that of the next upper disk.

7. In an earth anchor of a type employing a plurality of blades adapted to be extended from a stacked position, a guide pin penetrating the blades at a position near the respective peripheries thereof to provide an axis of extension, a flange eccentrically secured to the guide pin and a stub located on the upper surface of the top blade of the stack at a fixed radial distance from the guide pin axis whereby rotation of the top blade about the axis of extension causes the stub to follow a path of changing radial displacement from the flange periphery.

8. In an earth anchor of a type employing a plurality of blades, n in number, adapted to be successively extended from a stack, a guide pin penetrating the blades collectively at a position adjacent the respective peripheries thereof to provide an axis of extension, a flange eccentrically secured to the guide pin in abutting engagement with the uppermost blade, an uprising stub located on the uppermost blade at a fixed radial distance from the guide pin axis, and depending lugs respectively affixed to the peripheries of the upper $n-1$ blades with the location of the depending lugs being such that blade revolution about the axis of extension measured in degrees of angular displacement from the original stack position is determined in accordance with

$$N\left(\frac{360}{n}\right)$$

where N is a number corresponding to the blade position in the stack with N for the lowermost blade being equal to 0 and N for the uppermost blade being equal to $n-1$.

9. In an earth anchor of a type employing a plurality of blades adapted to be extended from a stacked position, a tube having one end thereof eccentrically flared penetrating the blades at a position near the respective peripheries thereof to provide an axis of extension for the blades and a stub located on the upper surface of the top blade of the stack at a fixed radial distance from the tube axis whereby rotation of the top blade about the axis of extension causes the stub

to follow a path of changing radial displacement from the periphery of the flared end of the tube.

10. The earth anchor of claim 9 including downwardly extending hollow projections positioned near the peripheries of each of the blades in such manner that the respective projections nest in the hollows of the projections of the blades successively positioned below when the blades are stacked.

11. The earth anchor of claim 10 wherein each of the blades includes a corrugation defining an arc of a circle having the center thereof along the axis of blade extension and radially displaced therefrom to permit nesting of the corrugations when the blades are stacked.

12. An expanding anchor comprising a plurality of blades adapted in a closed state to be stacked one above the other, a tubular member having a smaller external diameter at one end portion than at the other end portion thereof and the centers of said portions being radially displaced, said smaller diameter end portion extending through all of the disks in the vicinity of the disk circumference for locating the disks relative to one another and a stub secured to the uppermost blade of the stack at a fixed radial distance from the axis of said smaller end portion whereby rotation of the uppermost blade causes the stub to follow a path of changing radial displacement from the periphery of the larger diameter end portion.

13. An expanding earth anchor comprising a plurality of blades adapted in a closed state to be stacked one above the other, a tubular member having a smaller external dimension at one end portion than at the other end portion and the centers of said portions being radially displaced, said end portion of smaller dimension extending through all of the disks in the vicinity of the disk circumference for locating the disks relative to one another and a stub secured to the top blade of the stack at a fixed radial distance from the axis of the end portion of smaller dimension whereby rotation of the top blade causes the stub to follow a path of changing radial displacement from the periphery of the end portion of greater dimension.
